RETINOSCOPE HEAD

Raymond F. E. Stegeman, Greece, N. Y., assignor to
Bausch & Lomb Optical Company, Rochester, N. Y., a
corporation of New York

Application December 29, 1954, Serial No. 33,740

Term of patent 14 years

(Cl. D57—1)

FIG. 1

FIG. 2

FIG. 3

This application is a continuation-in-part of my application for patent Serial No. D24,147, filed March 23, 1953, now abandoned.

Fig. 1 is a rear elevational view of a retinoscope head showing my new design.

Fig. 2 is a front elevational view thereof.

Fig. 3 is a side elevational view thereof.

I claim:

The ornamental design for a retinoscope head, substantially as shown.
